UNITED STATES PATENT OFFICE.

FRITZ A. ERICSON, OF CHICAGO, ILLINOIS, ASSIGNOR OF ONE-HALF TO NELLIE C. BENSON AND HJALMAR PETERSON.

ROUND-CORNERING MACHINE FOR BOOK COVERS.

Application filed August 12, 1922. Serial No. 581,360.

To all whom it may concern:

Be it known that I, FRITZ A. ERICSON, a citizen of the United States, and a resident of Chicago, Cook County, and State of Illinois, have invented certain new and useful Improvements in Round-Cornering Machines for Book Covers, of which the following is declared to be a full, clear, and exact description.

10 This invention relates to round cornering machine for book covers, and its principal object is to provide an automatically operating machine for folding down rounded corner portions of the coverings of book covers and analogous articles. Another object is to provide a simple, practical, and efficient machine for accomplishing this purpose. Another object is to provide a round cornering machine with improved means for plaiting or gathering the covering material at round corners, and folding down the plaits or folds upon the body portion of the cover. Other objects and advantages will appear in the course of this specification, and with said 25 objects and advantages in view, this invention consists in the several novel features of construction, arrangement and combination of parts hereinafter fully set forth and claimed.

30 The invention is clearly illustrated in the drawings accompanying this specification, in which:

Fig. 1, is a plan of a round cornering machine embodying a simple form of the present invention; Fig. 2, is an end view of the front end of the machine looking in the direction of arrow 2 in Fig. 1; Fig. 3 is a detail side view of a certain stop device looking in the direction of the arrow 3 in Fig. 4; Fig. 4, is a detail end view of a certain finger bar and bar depressing cam, the base plate of the machine being shown in vertical cross section taken on line 4-4 of Fig. 1; Fig. 5 is an end view of said finger bar, showing the base plate in section, taken on line 5-5 of Fig. 1; Fig. 6, is a detail vertical longitudinal section of the finger bar taken on line 6-6 of Fig. 1; Fig. 7, is a vertical, longitudinal section taken on line 7-7 of Fig. 1; Fig. 8, is a vertical, longitudinal section taken on line 8-8 of Fig. 1; Fig. 9, is a cross section taken on line 9-9 of Fig. 1; Fig. 10, is a plan of the plaiting finger and its operating mechanism and showing a book cover with one of its covers

being acted on; Fig. 11, is a detail view of the plaiting finger and a mandrel or shoe partly in side elevation and partly in vertical, longitudinal section; Fig. 12, is a view of the same parts but showing them in a 60 different position; Fig. 13 is a plan of the shoe seen in Figs. 11 and 12; and Fig. 14 is a plan of a fragment of a book cover showing the covering folded and pasted down thereon.

Referring to said drawings, the reference character 15 designates a base plate, which may be of rectangular form, supported by legs 16. At the front end of the base plate is a book cover guide, which comprises two 70 guide bars 17 that are arranged at right angle to each other and are bolted or otherwise secured to the top of the base plate. One member 18 of the guide may be in the form of a thin plate, and is located at the 75 apex portion formed by the two guide bars 17. The plate 18 has a round edge 18', that conforms to the round corner of the book cover, which is to be operated on.

In front of the corner plate 18 is a mandrel 80 or shoe 19 which, in the operation of the machine, oscillates from an inoperative position (see Fig. 7) to an operative position, (see Fig. 11). Said shoe 19 is secured upon a rock shaft 20, journalled in standards 21, 85 which are secured to and extend up from base plate 15, and said shoe is yieldingly pressed in the direction of the corner plate 18, by a coiled spring 22 which surrounds the rock shaft 20 and engages at one end 90 with one of the standards 21 and at the other end with a collar 23, which is secured upon the rock shaft 20. A stop device is provided for stopping the shoe 19 at the position seen in Fig. 11 and said stop device 95 may comprise a collar 24 fast on the rock shaft, and a lug 25 on one of the standards 21. The collar 24 has an arm in which is threaded an adjustment screw 26 which is adapted to strike against the lug 25 when the shoe reaches the position seen in Fig. 11. To permit the shoe to yield slightly and thereby accommodate itself to any slight variations in the thickness of book covers, the shoe is shown as slidably mounted on a 100 stem 27 that enters a socket in the shoe. A pin and slot connection 28 between the stem 27 and shoe 19 limits the movement of the shoe on the stem. A coiled compression spring 29 confined between the shoe and a 105

110

2
 collar 30 fast on the rock shaft 20, moves the shoe to its distended position but permits it to yield when pressure is applied against its under side. Its forward end or toe 19^a is rounded off as is seen in Fig. 13 so as to conform to the round corner of the book cover.

Above the corner plate 18 is a plaiting finger 32, and in its preferred form, the 10 plaiting finger has a U-shaped re-entrant portion 33 in its forward edge, and its lower face may be formed with a shallow lengthwise extending groove (see Fig. 9) to receive any slightly bulged portions of the 15 folded corner portions. The plaiting finger is supported by a finger bar 34 which, in the operation of the machine, is oscillated or rocked in a horizontal plane during the 20 plaiting and folding down operation of the finger. The finger is capable of moving forth and back in a direction lengthwise of the machine, and is mounted on said finger bar 34 so as to have a sliding connection therewith. As shown the finger has an up- 25 wardly extending shank 35 which is secured to a finger holding block 36 that has a stem 37 secured to it, which enters a bore in the finger bar 34 and is slidably mounted therein. The finger is vertically adjustable on 30 the block 36 and is secured thereto by a screw 38 which passes through a slot in the shank of the finger and is threadedly secured in the block 36.

The means for reciprocating the finger in 35 a direction lengthwise of the base plate, comprises a slide block 39 which has an arm 40 that overhangs the block 36, and is pivotedly connected to the block 36 on a vertical axis, whereby the finger bar and its plaiting 40 finger, may be rocked or oscillated upon said arm 40. The pivotal connection between the arm 40 and block 36 may comprise a stud or pin 41 threadedly secured in the arm 40 and entering a socket 42 in the upper face of 45 the block 36. The pivotal connection is further arranged so the the finger bar and its plaiting finger may be depressed, during the operation of the machine, so as to put pressure upon the folded plaits of the corner.

50 The slide block 39 is guided between guide rails or bars 43 which are secured to the base plate 15, and it is connected to a crank or crank wheel 44 by a link or connecting rod 45. The crank or crank wheel 44 is secured 55 upon the main drive shaft 46 of the machine, which shaft is journalled in bearing brackets 47 secured upon the base plate 15. During each operation of the machine the drive shaft 46 is given one complete turn, and the plaiting finger is thereby moved forward and 60 backward by the crank wheel 44, link 55, slide block 39, and connections between the slide block and finger.

At the commencement of a cycle operation, 65 the parts are in position illustrated in Figs. 1,

7, and 8 where it is seen that the finger 32 is retracted, and the shoe 19 is raised above the base plate. In this position of the parts, the book cover A (which is to be operated upon) is inserted underneath the shoe 19 and placed 70 against the guide bars 17 so as to bring its round corner portion into the U-shaped notch in the corner plate 18. In the sequence of movements of the several parts, the shoe 19 is first swung into the position seen in Fig. 75 11 where it stands upon the body portion of the book cover, with the rounded end of its toe immediately behind the upturned margin portion a^1 of the covering a^2 (which is to be folded down). The means for actuating the 80 shoe 19 will now be described. A hook 48 mounted upon any suitable support, engages with a shoulder 49 formed upon the collar 23, and holds the shoe 19 in its raised position against the action of the coiled spring 22. Mounted upon the slide block 39 is a roller 50 which underlies the hook 48, and at the commencement of a cycle of operation of the machine said roller 50 encounters a cam shaped or shoulder edge 51 on the underside of the hook 48, and lifts the hook, thereby disconnecting it from the shoulder 49 of the collar 23, and permitting the coiled spring 22 to swing the shoe 19 down upon the book cover, immediately behind the raised margin portion a^1 of the covering which is to be folded down. By referring to Fig. 8, it will be seen that at the commencement of a cycle 90 operation, the wrist pin 52 (which connects the link 45 with the crank wheel 44), is moving upward and is approaching the dead center between the axis of the main drive shaft and the pin connection between the link 45 and slide block 39. It is during the 95 upward movement of the wrist pin 52 from the position shown, in full lines in Fig. 8 to that shown on the dotted lines, that the roller 50 encounters the cam edge 51 of the hook 48 and disconnects it from the shoulder 49 of the collar 23, thereby permitting the shoe 19 to be swung down by the spring 22. The further rotation of the crank wheel 44 through one hundred and eighty degrees, from the position seen in the dotted line in 100 Fig. 8, moves the finger 32 forward over the corner of the book cover and plaits and folds down the upturned corner portion a^1 of the covering a^2 . During the forward movement of the finger, the latter is pressed down upon the corner of the book cover and the 105 means for depressing and lifting the finger will now be described.

Journalled in bearing brackets 53 is a cam shaft 54 upon which is secured a cam block 55, against which bears a roller 56, that is mounted on the finger bar 34. One end of the finger bar rests on a cross bar 57 (see Fig. 6) and its other end is spring pressed 110 in an upward direction by a spring 58, which is interposed between the finger bar and base 115 120 125 130

plate (see Fig. 4). The cam block 55 contains a low face 55^a and a high face 55^b both concentric with the axis of the cam shaft and cam faces 55^c, 55^d which join said concentric faces. The face 55^a permits the spring 58 to lift the finger bar and finger, the cam face 55^c acts to depress the finger bar and finger as the latter starts to move forward, the concentric face 55^b holds the finger bar 3 depressed, with the finger in pressing engagement with the corner portion of the book cover, during the forward movement, and the cam face 55^d permits the spring to lift the finger bar and finger, during the 15 backward movement thereof.

The cam shaft 54 is geared to the main drive shaft 46 so as to rotate at the same speed, and as shown they are geared together by a sprocket chain 58 trained around 20 sprocket wheels 59, 60, mounted respectively on the shafts 46, 54.

Means are provided for swinging the shoe 19 upward while the finger is folding down the corner portion of the covering. In the 25 form of means shown, it comprises a link 61, which is pivotally secured to, and moves with the slide block 39 (see Figs. 8 and 9) and an arm 62 secured upon the rock shaft 20. The link 61 has a lost motion connection with the arm 62 whereby either may move independently of the other. Said lost motion connection may comprise a slot 63 in the link and a stud or pin 64 secured in the arm and entering said slot. When 30 the shoe is released by the hook 48, the spring 22 swings it down, and because of the lost motion connection the arm 62 is free to swing down into the position, seen in dotted lines in Fig. 8, and the shoe is 35 therefore free to swing down into the position seen in Fig. 11. During the initial forward movement of the slide block 39 and finger 32, the shoe remains at rest, pressing down on the book cover, until the end of the 40 slot 63 encounters the pin 64, whereupon the link 61 swings the arm 62 upward until the hook engages with the shoulder on the collar 23, thereby leaving the shoe in its 45 raised position while the link 61, slide block 39 and finger 32 are retracted.

For the purpose of gathering the plaits formed by the plaiting finger 32, the latter is oscillated, during at least some portion of its forward movement. The simple 50 means for oscillating the finger comprises a cam disc 65 fast on the main drive shaft, which disc has a wave like cam portion 66 that engages with a pair of anti-friction 55 rollers 67 mounted on a bar or other support 68, which is pivotally secured to the rear end of the finger bar 34 by a pin or screw 69. The rollers 67 are arranged one on each side of the disc 65, and the wave like cam portion is disposed on the disc in such 60 position as to oscillate the finger during

a portion at least, of its forward stroke. The cam disc contains a neutral position which extends between the cam part thereby permitting the finger to move back in a straight line.

The rear end of the finger bar is guided between two upright posts 70, and between the bar 57 and a rod 71 secured in the upper ends of the posts 70. A roller 72 secured on the lower face of the finger bar engages 75 with the bar 57 and prevents any forward movement of the finger bar.

In use the body portion and covering of the book covers are first pasted together and then prepared by folding down and securing the straight marginal portions a^3 of the backings upon the body portions a^4 leaving the round corner portions standing as seen at the right hand corner of the book cover A, in Fig. 10. The cover is then placed 80 in position on the base plate, using the guide 17, 18, to bring the unfinished corner at the proper place. In the operation of the machine, the shoe 19 swings down (when the rock shaft is released from the hook 48) 85 the finger 32 moves forward and down bending the upstanding corner portion a^1 down, and at the same time the finger is oscillated, thereby gathering in the plaits in neat folds, which are pressed down upon the corner portion of the body of the book cover and secured to it. The finger thereupon is lifted by the spring 58, (the cam 55 at this time having reached a position where its low side engages the roller 56) and the finger is 90 drawn back to its original position.

While the machine has been shown and described for use in folding down the round corners of book covers, it may be used in folding down round, curved or many sided 105 corners of coverings for other objects. It is capable of use on thick and thin covers, and corners of various shapes. The corner plate is removable and may be replaced by another one having a different form of 110 corner than the one shown.

More or less variation of the exact details of construction is possible without departing from the spirit of this invention; I desire, therefore, not to limit myself to 115 the exact form of the construction shown and described, but intend, in the following claims, to point out all of the invention disclosed herein.

I claim as new and desire to secure by 120 Letters Patent:

1. A round cornering machine comprising, in combination, an oscillatory shoe, a reciprocating plaiting finger, means for reciprocating said plaiting finger, and means, 125 operating in a predetermined timed relation to said finger reciprocating means, for oscillating said shoe.

2. A round cornering machine comprising, in combination, an oscillatory shoe, a 130

- reciprocating plaiting finger, means for reciprocating said plaiting finger, means for depressing said plaiting finger upon the material operated on, and means for oscillating said shoe in timed relation to the reciprocating movements of the plaiting finger.
3. A round cornering machine comprising, in combination, an oscillatory shoe, spring pressed in one direction, means for oscillating said shoe, a reciprocating plaiting finger, means for reciprocating said plaiting finger, means for raising said shoe against said spring pressure, means for releasably holding said shoe in raised position and means for releasing said shoe from said shoe holding means.
4. A round cornering machine comprising, in combination, an oscillatory shoe, spring pressed in one direction, means for oscillating said shoe, a reciprocating plaiting finger, actuating mechanism for reciprocating said plaiting finger, a link connection between said shoe and finger actuating mechanism including a lost motion device, means for holding said shoe in raised position against the action of the spring, and means for disconnecting said shoe holding means from the shoe.
5. A round cornering machine comprising, in combination, an oscillatory shoe, spring pressed in one direction, a rock shaft supporting said shoe, a reciprocating plaiting finger, finger actuating mechanism, an arm secured upon said rock shaft, a link connected with said finger actuating mechanism and having the lost motion connection with said arm, a shouldered member secured on said rock shaft, a hook arranged to engage with said shouldered member to thereby hold the shoe in raised position and, hook releasing means operated by the said finger actuating mechanism.
6. A round cornering machine comprising, in combination, an oscillatory shoe, spring pressed in one direction, a rock shaft supporting said shoe, a reciprocating plaiting finger, finger reciprocating mechanism, an arm secured upon said rock shaft, a link secured upon said finger actuating mechanism and having a lost motion connection with said arm, a stop device for limiting the movement of said shoe in one direction, a shouldered member secured upon said rock shaft, a hook arranged to engage with said shouldered member for holding the shoe in raised position, said hook having a cam face, and a cam engaging member connected with said finger actuating mechanism, for releasing said hook from said shouldered member.
7. A round cornering machine comprising a base plate, a book cover guide thereon, an oscillatory shoe located over said guide, a reciprocating plaiting finger, finger actuating mechanism including a reciprocating power transmitting member, and shoe ac-
- tuating mechanism operatively connected to said power transmitting member and operating in a predetermined timed relation with finger actuating mechanism.
8. A round cornering machine comprising, in combination, a base plate, a book cover guide thereon, a reciprocating plaiting finger, finger actuating mechanism, and means for depressing said finger upon the material acted on thereby.
9. A round cornering machine comprising, in combination, a base plate, a finger bar, a plaiting finger carried thereby and movable lengthwise thereof, finger actuating mechanism, a cam shaft, and a cam for depressing said finger bar.
10. A round cornering machine comprising, in combination, a finger bar, spring pressed in an upward direction, a cam shaft and a cam thereon for depressing said finger bar, a plaiting finger mounted on said finger bar and movable lengthwise thereof, and finger actuating mechanism for reciprocating said finger relative to said finger bar.
11. A round cornering machine comprising, in combination, a finger bar, a plaiting finger having a sliding connection with said finger bar, a reciprocating slide block connected with said plaiting finger, a main drive shaft, and connections between said main drive shaft and slide block for reciprocating said slide block.
12. A round cornering machine comprising, in combination, a reciprocating and oscillatory plaiting finger, a slide block connected thereto, a main drive shaft, a crank on said main drive shaft, a link connecting said crank with said slide block, and operative connections between said slide block and finger for oscillating the same.
13. A round cornering machine comprising, in combination, a finger bar, a plaiting finger guided by said finger bar to move in a direction lengthwise thereof, a slide block connected to said finger, a main drive shaft, a crank thereon, and a link connecting said crank with said slide block.
14. A round cornering machine comprising, in combination, a finger bar, spring pressed in an upward direction, a cam shaft and a cam thereon for depressing said finger bar, a plaiting finger, a block carrying said plaiting finger and having a stem guided in said finger bar, a slide block having an arm overhanging said finger supporting block, and a pin entering a socket in the top of said finger supporting block, and means for reciprocating said slide block.
15. In a round cornering machine, a reciprocating finger supporting block, and a plaiting finger having a U-shaped notch in its forward edge and having an up standing shank adjustably mounted on said finger supporting block.

16. In a round cornering machine, a rock shaft, a stem secured thereto, a shoe slidably mounted on said stem and having a limited outward movement thereon, and a coiled compression spring surrounding said stem and bearing against said shoe.

17. A round cornering machine comprising an oscillatory finger bar, means for oscillating said finger bar, a plaiting finger mounted on said finger bar and movable lengthwise thereof, finger reciprocating mechanism having a pivotal connection with said finger, a main drive shaft, and a cam disc thereon having cam faces engaging with said finger bar for oscillating it.

18. A round cornering machine comprising an oscillatory finger bar, means for oscillating said finger bar, a reciprocatory plaiting finger mounted thereon and mov-

able lengthwise thereof, finger actuating means having a pivotal connection with said finger, a main drive shaft, a cam disc mounted thereon and having wave like cam faces, and anti-friction rollers carried by said finger bar and engaging with said cam disc.

19. A round cornering machine comprising a shoe, a reciprocatory and oscillatory plaiting finger cooperating therewith, means for reciprocating and other means for oscillating said plaiting finger.

20. A round cornering machine comprising a shoe, a reciprocatory plaiting finger, means for reciprocating said plaiting finger, means for oscillating said finger horizontally, and other means for oscillating said finger vertically.

FRITZ A. ERICSON.
